GOLF TEE

Duncan A. MacInnes and Albert J. Allgoewer,
San Francisco, Calif.; said Allgoewer assignor
to said MacInnes

Application February 25, 1946, Serial No. 649,864

5 Claims. (Cl. 273—33)

1

This invention relates to golfing equipment, and more particularly to a golf tee.

Among the principal objects of this invention are the following: To provide a golf tee not susceptible to loss in normal use; to provide a golf tee having a ball supporting member adapted to offer no resistance to the passage of a club head; to provide a golf tee practically indestructible in normal use; and to provide a golf tee having an anchoring peg, a swivel arm for supporting a golf ball, and novel means for attaching the arm to the peg.

Other objects and advantages of the invention will be apparent from the following description taken in conjunction with the drawings forming a part of this specification, and in which:

Figure 1 is a plan view of the golf tee embodied in the invention with a golf ball supported thereon;

Figure 2 is a view in elevation of the golf tee with a golf ball supported thereon;

Figure 3 is a view in section taken along lines 3—3 of Figure 1; and

Figure 4 is a view in section taken along lines 4—4 of Figure 3.

Referring to the drawing for more specific details of the drawing, the golf tee comprises an anchoring peg indicated generally at 12 and a wire arm 14 having at one end thereof an offset loop 16 and at the other end thereof a leg 18, bent at a right angle to the arm 14. The peg 12, unitary as to structure and being preferably made of a metal, such as aluminum, comprises a pointed end portion 20, a bevelled shoulder 22, a cylindrical upper portion 24 having a peripheral channel 26 therein, a drilled hole 28 extending axially into the cylindrical portion 24 past the peripheral channel 26, and a drilled hole 30 substantially larger in diameter than the drilled hole 28 and extending diametrically through the peg at the channel 26.

In assembling the golf tee, the leg 18 is introduced into the drill hole 28, said hole being of such a diameter as to comfortably receive the leg, and the leg is then swaged within the peg 12 through the hole 30 to provide a swaged portion 32 on the leg 18 to prevent relative longitudinal movement between the peg 12 and said leg.

The pointed portion 20 of the peg 12 may be inserted in the ground to any desired depth limited by the bevelled shoulder 22, and a golf ball 34 is then placed on the loop 16. The arm 14 is normally between the peg 12 and the golfer and is substantially aligned with the golf club when the club is in the position of address. When the

ball 34 is struck, the arm 14 freely rotates, the swaged portion 32 of the leg 18 serving the two-fold purpose of locking the arm 14 against disengagement from the peg 12 and causing a minimum of frictional resistance during free rotation of the arm. Due to the free rotation characteristic of the arm 14, it is practically impossible to damage said arm by an inadvertent striking of the arm with the driving head of the golf club.

10 While the preferred embodiment of this invention has been shown and described, it is understood that modifications of this embodiment may be made within the spirit of the invention and the scope of the appended claims.

15 What we claim as new and desire to secure by Letters Patent is:

1. A golf tee comprising an anchoring peg, an axial passage in the upper portion thereof, a diametral passage intercepting the axial passage and having a larger diameter than said axial passage, a spring wire arm having a loop at one end and a leg at the other end, said leg being freely rotatable in the axial passage and having a portion with a lateral dimension greater than 25 the diameter of the axial passage in registry with the diametral passage.

2. A golf tee comprising an anchoring peg having a pointed lower portion and a cylindrical upper portion, an axial passage extending inwardly of the cylindrical portion, a diametral passage through the cylindrical portion intercepting the axial passage and being larger than said passage, a spring wire arm having a loop at one end and a leg at the other end normal to the arm, 35 said leg being freely rotatable in the axial passage and having a portion with a lateral dimension greater than the diameter of the axial passage registering with the diametral passage.

3. A golf tee comprising an anchoring peg having a pointed lower portion and a cylindrical upper portion, a peripheral channel in the cylindrical portion, an axial passage extending within the cylindrical portion and past the channel, a diametral passage through the channel intercepting the axial passage and being larger than said passage, a spring wire arm having a ball-supporting loop at one end and a leg at the other end normal to the arm, said leg being received within the axial passage and being freely rotatable therein, and said leg having a swaged portion 45 registering with the diametral passage.

4. A golf tee comprising an anchoring peg having a pointed lower portion and a cylindrical upper portion, a circular peripheral channel in the cylindrical portion, an axial passage extend-

ing within the cylindrical portion and past the channel, a diametral passage larger than the axial passage extending through the cylindrical portion at the channel and intercepting the axial passage, a spring wire arm having a ball-supporting loop at one end and a leg at the other end normal to the arm and extending within the axial passage, said leg being slightly smaller in diameter than the axial passage and being freely rotatable therein, and said leg being locked against relative longitudinal movement with respect to the peg by a swaged portion on the leg registering with the diametral passage.

5. A golf tee comprising an anchoring peg, an axial passage in the upper portion thereof, another passage in said peg of larger diameter than said axial passage and transversely intercepting said axial passage, an arm having a loop at one end and leg at the other end normal to the arm

10 and extending within said axial passage past said other passage, and means carried by said leg for both permanently connecting said arm to said anchoring peg and providing a bearing support for said arm, said means comprising a portion of said leg in registry with both passages and having a transverse dimension intermediate in value of the diametral dimensions of said passages.
